OIL CRACKING APPARATUS

Frederic M. Pyzel, Piedmont, Calif., assignor to
Universal Oil Products Company, Chicago, Ill.,
a corporation of South Dakota

Application August 11, 1928, Serial No. 298,900
Renewed September 16, 1932

2 Claims. (Cl. 196—107)

This invention relates to the conversion of heavier hydrocarbons into lighter hydrocarbons by means of heat and superatmospheric pressure for the production of gasoline-like motor fuels and other desirable products having a higher commercial value than the charging stock.

One of the objects of the invention is to provide a continuous process and apparatus for cracking oils by which a high yield of the desired products is obtained with a minimum production of coke, carbon and/or fixed gases, resulting in high efficiency and economy of operation.

While I have shown the invention as applied to a process and apparatus wherein the oil is first heated, then passed to a separator and/or conversion chamber wherein separation is permitted of vaporous from non-vaporous products of reaction and the latter removed from the process and apparatus, while the vapors are fractionated and so-called reflux condensate returned for retreatment, it is understood that the invention is equally applicable to all cracking processes and apparatus operating under pressure wherein the oil is heated to a cracking temperature by being caused to pass first through a heating coil then to a separating and/or reaction chamber, irrespective of the arrangement of connected parts.

Difficulty has been experienced in the operation of cracking plants due to the formation of tar-like coke-containing residues and the formation and deposit of an objectionable amount of solid coke or carbon for each barrel of oil treated, which was permitted to accumulate in large drums or reaction chambers. The accumulation of such a large amount of coke is objectionable, since it decreases the continuity and efficiency of the operation and the coke-containing residues are unsatisfactory for sale and use as fuel.

I have found that this formation of coke depositing in the chambers or removed with the liquid residue from the process, is caused by the prolonged exposition to a cracking temperature of the non-vaporized oil in the reaction chamber where a liquid level is maintained by allowing a substantial body of non-vaporized oil to remain in the chamber.

As one of the features of my invention, to overcome this difficulty, I propose to withdraw the non-vaporized oil from the reaction chamber of the process at such a rate that the liquid level in the chamber is as low as is possible without drawing off vapors through the residuum draw-off lines.

As another feature of the invention I provide for the withdrawal of the vapors from the reac-

tion chamber from the end of the chamber opposite to that at which the hot oil from the heating coil is discharged. Thus, as the oil enters the reaction chamber at one end and the vapors are withdrawn at the other end, every fraction of the oil and vapors is forced to travel through the large vapor space of the chamber, the time element is more equally distributed on every part of the vapors, and it avoids the short-circuiting of large portions of insufficiently cracked vapors that takes place when the oil enters and the vapors leave the chamber at the same end. The cracking takes place more evenly on all fractions of vapors, which results in cracking toward lighter condensable products rather than toward non-condensable gases.

Further, I have found that by forcing the vapors downward through the large vapor space of the chamber, I obtain better results, increased cracking to gasoline, decreased formation of gases and coke, than with a process where the vapors are caused to travel upwardly through the chamber, that is to say, where the oil enters the chamber toward the bottom and the vapors discharge from the top of the chamber.

Other features of the invention will appear from the following description and from the attached drawing, where the single figure is a diagrammatic view, partly in section and partly in elevation, of an apparatus suitable to carry out my invention.

Referring more particularly to the drawing, the oil is withdrawn from any suitable source of supply, not shown, through line 1 and forced by pump 2 into direct feed line 3, whereby it is charged into heating coil 4 positioned in suitable furnace 5. The oil, heated to cracking temperature in heating coil 4, is discharged therefrom through transfer line 6, having valve 7, into the upper part of reaction chamber 8. There vapors separate from unvaporized oil and the latter may be withdrawn intermittently or continuously from the bottom of the chamber 8 through lines 9, controlled by valves 10. The withdrawal of the non-vaporized oil from chamber 8 may be effected at such a rate that any desired level of liquid oil may be maintained in chamber 8, but I preferably regulate such withdrawal so that a very low level is maintained therein, for instance, about a foot of oil maintained in the bottom of chamber 8 above the lowermost point.

The vapors separated in chamber 8 are withdrawn therefrom through line 11, having valve 12. As a feature of the invention, vapor draw-off line 11 preferably extends into the inside of chamber 55

2

8 by means of extension 11a, which terminates in the lower part of chamber 8 preferably near the vertical axis thereof, and above the level of non-vaporized oil maintained therein. The point of withdrawal of vapors from the chamber can be changed, according to the results desired and the conditions of operation, by changing the length of extension 11a. Suitable nozzles, bushings and packing provide for a tight joint between vapor line 11, extension 11a and the wall of chamber 8.

Vapors leaving chamber 8 through lines 11 and 11a pass into dephlegmator 13, where they are fractionated by means of a suitable cooling medium injected into the top of the dephlegmator through line 14, having valve 15.

If desired, a part or all of the raw oil charged into the system by means of pump 2 may be diverted from line 3 by suitably manipulating valve 3a on said line 3 and valve 16 on line 17, and said raw oil may then be charged into the dephlegmator 13 through said line 17 to serve as a cooling medium for the vapors evolved in the process.

The reflux condensate separated in the dephlegmator 13 is discharged, alone or mixed with pre-heated raw oil from the bottom of the dephlegmator 13 through line 18, having valve 19, and it is charged by means of pump 20 into the feed line 3 where, after mixing with the raw oil which may have been fed directly through line 3, it re-enters the heating tubes 4.

The vapors which remain un-condensed after passage through dephlegmator 13 are withdrawn therefrom through line 21, having valve 22, and passed through conventional condenser 23, being collected as liquid distillate in receiver 24, having gas release valve 25 and distillate draw-off valve 26.

As an illustration of the operation of the process California fuel oil having a gravity of about 18° Bé. may be treated under a pressure of about 150 pounds and at a temperature of about 880° F., with the production of about 35% of 437° F. gasoline, of a residuum containing less than 1% of sludge or B. S., and of less than 1 pound of coke per barrel of raw oil treated.

These conditions are not to be taken as a limitation of the scope of the invention, but as an illustration of the beneficial results of my process. The operating conditions will vary with the various charging stocks used and with the various products which may be desired.

While I have illustrated a form of apparatus suitable to carry out the process of the present invention, other designs may be used and found suitable to carry out the method and obtain the results of this invention; and I do not intend to limit myself to the particular form of apparatus shown.

A small by-pass line 27 having valve 28 may connect the top of the chamber 8 with vapor line 11, and valve 28 which remains normally closed may be opened intermittently for short periods to prevent accumulation of air or non-condensable gas in the upper part of the chamber.

I claim as my invention:

1. An apparatus for hydrocarbon oil conversion, comprising in combination a heating tube mounted in a heating zone, an enlarged drum in communication with the outlet of said tube, a liquid draw-off in cooperative communication with the lower portion of said drum and a vapor draw-off from said drum having an extension projecting for a substantial distance into said drum, and a valve controlled by-pass establishing communication between the upper portion of said drum and that portion of the vapor draw-off disposed outside the drum.

2. An apparatus for hydrocarbon oil conversion, comprising in combination a heating tube mounted in a heating zone, an enlarged drum in communication with the outlet of said tube, a liquid draw-off in cooperative communication with the lower portion of said drum and a vapor draw-off from said drum having an extension projecting for a substantial distance into said drum, and a valved by-pass establishing communication between the upper portion of said drum and said vapor draw-off.

FREDERIC M. PYZEL.
